UNITED STATES PATENT OFFICE

BYERS W. KADEL, OF BALTIMORE, MARYLAND, ASSIGNOR, BY MESNE ASSIGNMENTS,
TO THE SYMINGTON COMPANY, A CORPORATION OF MARYLAND

DRAFT RIGGING

Application filed May 6, 1921. Serial No. 467,349.

The invention relates to draft rigging for railway cars, and more particularly to means for operatively connecting a coupler to the cushioning mechanism of the draft rigging.

The principal object of my invention, broadly stated, is to provide a simple, strong, reliable and efficient coupler connecting means or yoke member adapted for use with the modern types of cushioning mechanism now commonly employed.

Another object of my invention is to provide simple means for operatively connecting the coupler and cushioning mechanism by which the coupler is pivotally connected to the draft rigging or cushioning mechanism so as to permit said coupler to move radially during the passage of a car around curves without placing upon said connecting means distorting or destructive forces.

A still further object of the invention is to provide a coupler connecting means or yoke member adapted to engage the cushioning mechanism at a plurality of spaced points to thereby equalize the strain upon the cushioning mechanism to prevent the distortion thereof.

Other objects of the invention will hereinafter appear from the more detailed description hereof particularly when taken in connection with the accompanying drawings wherein I have illustrated two embodiments of the invention.

In the drawings,—

Figure 1 is a top plan view of a draft rigging and the associated parts of a car underframe embodying my invention.

Figure 2 is a central longitudinal vertical sectional view of the construction shown in Fig. 1, the cushioning mechanism being shown in elevation; and

Figure 3 is a view similar to Fig. 2, illustrating a slight modification.

Throughout the specification and drawings like parts are indicated by like reference characters.

The numeral 1 designates the center or draft sills of a railway car to which are connected, preferably by means of rivets 2, a pair of stop lugs 3. Each stop lug is provided with a rearwardly facing abutment or

shoulder 4 normally adapted to engage the front face of the follower 5 of the cushioning mechanism 6. In the preferred embodiment of the invention the cushioning mechanism is maintained against bodily rearward movement by means of a centrally disposed stop casting 7 which bridges the space between the sills 1 and is connected to the inner faces thereof preferably by means of rivets 8. The said stop 7 for convenience is substantially of I section having a central longitudinally extending web 9 and a transversely extending web 10, the last named web forming the stop face of the said stop casting. If desired, the stop face 10 may be reinforced by a longitudinally extending centrally disposed rib 11, clearly shown in Fig. 1. The coupler 12 is provided on the inner end of its stem with oppositely extending vertically arranged pivot bosses 13, the front faces of which are struck on a radius equal to the radius of the pivot boss.

The coupler connecting means comprises a plurality of closed loops or yoke members 14 which are adapted to straddle the cushioning mechanism 6 and which at their forward and rear ends respectively extend above and below the stops 3 and 7, as clearly shown in Fig. 2. At their forward ends the loops 14 are provided with curved bearing faces 15 adapted to engage the curved outer face of the respective pivot boss 13 of the coupler 12. The inner faces of each loop on opposite sides of the pivot 13 may be provided with fins or ribs 16 which serve to always maintain the pivot boss 13 on the longitudinal center line of the car.

The upper and lower side edges of the follower 5 are notched as at 17 so as to accommodate the longitudinally extending arms of the respective loops 14.

In Fig. 3 I provide each loop member 18 adjacent its rear end with a transversely extending web and an upright flange 19 and 20, respectively, thus making the transversely extending rear portion of each loop of substantially H shape in cross section. The object of thus reinforcing the rear end of the loop is to provide contact points to engage the divided stop member 21 which is sub-

stituted in this construction for the single centrally disposed stop member 7 shown in Figs. 1 and 2. Except for the modification herein specifically noted the construction of Fig. 3 is in all respects identical with the construction of Figs. 1 and 2, and therefore need not be further described.

The operation of the device will be obvious to those skilled in the art, since on the forward movement of the coupler from normal, the engagement of the coupler boss 13 with the respective loops 14 will carry the loop members 14 with the coupler, thus moving the cushioning mechanism 6 toward the follower 5; and since the movement of this follower is prevented by the engagement thereof with the stop members 3 the cushioning mechanism will be compressed and will yieldingly resist the outward movement of the coupler. Under an inward or buffing movement of the coupler the rear end of the coupler bearing directly against the follower 5 will force the same inwardly and hence compress the cushioning mechanism between the stop member 3 and the stop member 7 of Figs. 1 and 2, or the stop members 21 of Figure 3, as the case may be.

While I have not illustrated any means for maintaining the draft rigging in place, it is obvious that any of the many forms of construction now commonly employed may be used with my device. It is also obvious that by my construction I am enabled to assemble and disassemble the draft rigging independently of the coupler connecting means by simply removing the cushioning mechanism 6 and then sliding the follower 5 rearwardly sufficiently to permit the follower to be rotated so as to clear the end portions thereof from engagement with the lower loop member 14. Correspondingly to replace the draft rigging this operation is reversed.

I claim:

1. In a draft rigging, the combination with a coupler having oppositely disposed pivot bosses formed thereon, of a cushioning mechanism therefor, stops for said mechanism, and means for operatively connecting the coupler to said mechanism, said means including a pair of independent vertically separated horizontally disposed yoke members surrounding said cushioning mechanism.

2. In a draft rigging, the combination with a coupler furnished with integral yoke engaging portions and a cushioning mechanism for said coupler, of means for operatively connecting the same, said means including vertically spaced members each of which embraces the said cushioning mechanism and is pivotally connected to one of said integral portions formed on the said coupler.

3. In a draft rigging, the combination with draft sills having front and rear stop members connected thereto, of a coupler, a cushioning mechanism adapted to cooperate there-

with, and means for operatively connecting said coupler and cushioning mechanism, said means including a pair of independent spaced horizontally disposed yokes, each of which embraces the cushioning mechanism and is adapted to pivotally engage a boss formed on the said coupler.

4. In a draft rigging, the combination with a coupler, of a cushioning mechanism therefor, pivot bosses formed on said coupler, and means for operatively connecting said coupler and cushioning mechanism, said means comprising a pair of horizontally disposed vertically spaced yoke members each adapted to engage one of the said pivot bosses on said coupler and embrace said cushioning mechanism.

In testimony whereof I affix my signature.
